[57] CLAIM

The ornamental design for a combined vehicle ornament and advertising device, as shown.

DESCRIPTION

FIG. 1 is a front elevational view of a combined vehicle ornament and advertising device, showing my new design;

FIG. 2 is a side elevational view thereof, shown with the central panel rotated;

FIG. 3 is a perspective view thereof;

FIG. 4 is a top plan view thereof;

FIG. 5 is a front elevational view of a second embodi-

ment of a combined vehicle ornament and advertising device;

FIG. 6 is a side elevational view thereof, shown with the central panel rotated;

FIG. 7 is a perspective view thereof;

FIG. 8 is a top plan view thereof;

FIG. 9 is a front elevational view of a third embodiment of a combined vehicle ornament and advertising device;

FIG. 10 is a side elevational view thereof, shown with the central panel rotated;

FIG. 11 is a perspective view thereof;

FIG. 12 is a side elevational view thereof, shown with the central panel rotated;

FIG. 13 is a perspective view thereof;

FIG. 14 is a top plan view thereof;

FIG. 15 is a front elevational view of a ninth embodiment of a combined vehicle ornament and advertising device;

FIG. 16 is a side elevational view thereof, shown with the central panel rotated;

FIG. 17 is a perspective view thereof;

FIG. 18 is a top plan view thereof;

FIG. 19 is a front elevational view of a tenth embodiment of a combined vehicle ornament and advertising device;

FIG. 20 is a side elevational view thereof, shown with the central panel rotated;

FIG. 21 is a perspective view thereof;

FIG. 22 is a top plan view thereof;

FIG. 23 is a front elevational view of an eleventh embodiment of a combined vehicle ornament and advertising device;

FIG. 24 is a side elevational view thereof, shown with the central panel rotated;

FIG. 25 is a perspective view thereof;

FIG. 26 is a top plan view thereof;

FIG. 27 is a front elevational view of a twelfth embodiment of a combined vehicle ornament and advertising device;

FIG. 28 is a side elevational view thereof, shown with the central panel rotated;

FIG. 29 is a perspective view thereof;

FIG. 30 is a top plan view thereof;

FIG. 31 is a front elevational view of a thirteenth embodiment of a combined vehicle ornament and advertising device;

FIG. 32 is a side elevational view thereof, shown with the central panel rotated;

FIG. 33 is a perspective view thereof;

FIG. 34 is a top plan view thereof;

FIG. 35 is a front elevational view of a fourteenth embodiment of a combined vehicle ornament and advertising device;

FIG. 36 is a side elevational view thereof, shown with the central panel rotated;

FIG. 37 is a perspective view thereof;

FIG. 38 is a top plan view thereof;

FIG. 39 is a front elevational view of a fifteenth embodiment of a combined vehicle ornament and advertising device;

FIG. 40 is a side elevational view thereof, shown with the central panel rotated;

FIG. 41 is a perspective view thereof;

FIG. 42 is a top plan view thereof;

FIG. 43 is a front elevational view of a sixteenth embodiment of a combined vehicle ornament and advertising device;

FIG. 44 is a side elevational view thereof, shown with the central panel rotated;

FIG. 45 is a perspective view thereof;

FIG. 46 is a top plan view thereof;

FIG. 47 is a front elevational view of a seventeenth embodiment of a combined vehicle ornament and advertising device;

FIG. 48 is a side elevational view thereof, shown with the central panel rotated;

FIG. 49 is a perspective view thereof;

FIG. 50 is a top plan view thereof;

FIG. 51 is a front elevational view of an eighteenth embodiment of a combined vehicle ornament and advertising device;

FIG. 52 is a side elevational view thereof, shown with the central panel rotated;

FIG. 53 is a perspective view thereof;

FIG. 54 is a top plan view thereof;

FIG. 55 is a front elevational view of a nineteenth embodiment of a combined vehicle ornament and advertising device;

FIG. 56 is a side elevational view thereof, shown with the central panel rotated;

FIG. 57 is a perspective view thereof;

FIG. 58 is a top plan view thereof;

FIG. 59 is a front elevational view of a twentieth embodiment of a combined vehicle ornament and advertising device;

FIG. 60 is a side elevational view thereof, shown with the central panel rotated;

FIG. 61 is a perspective view thereof;

FIG. 62 is a top plan view thereof;

FIG. 63 is a front elevational view of a twenty-first embodiment of a combined vehicle ornament and advertising device;

FIG. 64 is a side elevational view thereof, shown with the central panel rotated;

FIG. 65 is a perspective view thereof;

FIG. 66 is a top plan view thereof;

FIG. 67 is a front elevational view of a twenty-second embodiment of a combined vehicle ornament and advertising device;

FIG. 68 is a side elevational view thereof, shown with the central panel rotated;

FIG. 69 is a perspective view thereof;

FIG. 70 is a top plan view thereof;

FIG. 71 is a front elevational view of a twenty-third embodiment of a combined vehicle ornament and advertising device;

FIG. 72 is a side elevational view thereof, shown with the central panel rotated;

FIG. 73 is a perspective view thereof;

FIG. 74 is a top plan view thereof;

FIG. 75 is a front elevational view of a twenty-fourth embodiment of a combined vehicle ornament and advertising device;

FIG. 76 is a side elevational view thereof, shown with the central panel rotated;

FIG. 77 is a perspective view thereof;

FIG. 78 is a top plan view thereof;

FIG. 79 is a front elevational view of a twenty-fifth embodiment of a combined vehicle ornament and advertising device;

FIG. 80 is a side elevational view thereof, shown with the central panel rotated;

FIG. 81 is a perspective view thereof;

FIG. 82 is a top plan view thereof;

FIG. 83 is a front elevational view of a twenty-sixth embodiment of a combined vehicle ornament and advertising device;

FIG. 84 is a side elevational view thereof, shown with the central panel rotated;

FIG. 85 is a perspective view thereof;

FIG. 86 is a top plan view thereof;

FIG. 87 is a front elevational view of a twenty-seventh embodiment of a combined vehicle ornament and advertising device;

FIG. 88 is a side elevational view thereof, shown with the central panel rotated;

FIG. 89 is a perspective view thereof;

FIG. 90 is a top plan view thereof;

FIG. 91 is a front elevational view of a twenty-eighth embodiment of a combined vehicle ornament and advertising device;

FIG. 92 is a side elevational view thereof, shown with the central panel rotated;

FIG. 93 is a perspective view thereof;

FIG. 94 is a top plan view thereof;

FIG. 95 is a front elevational view of a twenty-ninth embodiment of a combined vehicle ornament and advertising device;

FIG. 96 is a side elevational view thereof, shown with the central panel rotated;

FIG. 97 is a perspective view thereof;

FIG. 98 is a top plan view thereof;

FIG. 99 is a front elevational view of a thirtieth embodiment of a combined vehicle ornament and advertising device;

FIG. 100 is a side elevational view thereof, shown with the central panel rotated;

FIG. 101 is a perspective view thereof;

FIG. 102 is a top plan view thereof;

FIG. 103 is a front elevational view of a thirty-first embodiment of a combined vehicle ornament and advertising device;

FIG. 104 is a side elevational view thereof, shown with the central panel rotated;

FIG. 105 is a perspective view thereof;

FIG. 106 is a top plan view thereof;

FIG. 107 is a front elevational view of a thirty-second embodiment of a combined vehicle ornament and advertising device;

FIG. 108 is a side elevational view thereof, shown with the central panel rotated;

FIG. 109 is a perspective view thereof;

FIG. 110 is a top plan view thereof;

FIG. 111 is a front elevational view of a thirty-third embodiment of a combined vehicle ornament and advertising device;

FIG. 112 is a side elevational view thereof, shown with the central panel rotated;

FIG. 113 is a perspective view thereof;

FIG. 114 is a top plan view thereof;

FIG. 115 is a front elevational view of a thirty-fourth embodiment of a combined vehicle ornament and advertising device;

FIG. 116 is a side elevational view thereof, shown with the central panel rotated;

FIG. 117 is a perspective view thereof;

FIG. 118 is a top plan view thereof;

FIG. 119 is a front elevational view of a thirty-fifth embodiment of a combined vehicle ornament and advertising device;

FIG. 120 is a side elevational view thereof, shown with the central panel rotated;

FIG. 121 is a perspective view thereof;

FIG. 122 is a top plan view thereof;

FIG. 123 is a front elevational view of a thirty-sixth embodiment of a combined vehicle ornament and advertising device;

FIG. 124 is a side elevational view thereof, shown with the central panel rotated;

FIG. 125 is a perspective view thereof;

FIG. 126 is a top plan view thereof;

FIG. 127 is a front elevational view of a thirty-seventh embodiment of a combined vehicle ornament and advertising device;

FIG. 128 is a side elevational view thereof, shown with the central panel rotated;

FIG. 129 is a perspective view thereof;

FIG. 130 is a top plan view thereof;

FIG. 131 is a front elevational view of a thirty-eighth embodiment of a combined vehicle ornament and advertising device;

FIG. 132 is a side elevational view thereof, shown with the central panel rotated;

FIG. 133 is a perspective view thereof;

FIG. 134 is a top plan view thereof;

FIG. 135 is a front elevational view of a thirty-ninth embodiment of a combined vehicle ornament and advertising device;

FIG. 136 is a side elevational view thereof, shown with the central panel rotated;

FIG. 137 is a perspective view thereof;

FIG. 138 is a top plan view thereof;

FIG. 139 is a front elevational view of a fortieth embodiment of a combined vehicle ornament and advertising device;

FIG. 140 is a side elevational view thereof, shown with the central panel rotated;

FIG. 141 is a perspective view thereof;

FIG. 142 is a top plan view thereof;

FIG. 143 is a front elevational view of a forty-first embodiment of a combined vehicle ornament and advertising device;

FIG. 144 is a side elevational view thereof, shown with the central panel rotated;

FIG. 145 is a perspective view thereof;

FIG. 146 is a top plan view thereof;

FIG. 147 is a front elevational view of a forty-second embodiment of a combined vehicle ornament and advertising device;

FIG. 148 is a side elevational view thereof, shown with the central panel rotated;

FIG. 149 is a perspective view thereof;

FIG. 150 is a top plan view thereof;

FIG. 151 is a front elevational view of a forty-third embodiment of a combined vehicle ornament and advertising device;

FIG. 152 is a side elevational view thereof, shown with the central panel rotated;

FIG. 153 is a perspective view thereof;

FIG. 154 is a top plan view thereof;

FIG. 155 is a front elevational view of a forty-fourth embodiment of a combined vehicle ornament and advertising device;

FIG. 156 is a side elevational view thereof, shown with the central panel rotated;

FIG. 157 is a perspective view thereof;

FIG. 158 is a top plan view thereof;

FIG. 159 is a front elevational view of a forty-fifth embodiment of a combined vehicle ornament and advertising device;

FIG. 160 is a side elevational view thereof, shown with the central panel rotated;

FIG. 161 is a perspective view thereof;

FIG. 162 is a top plan view thereof;

FIG. 163 is a front elevational view of a forty-sixth embodiment of a combined vehicle ornament and advertising device;

FIG. 164 is a side elevational view thereof, shown with the central panel rotated;

FIG. 165 is a perspective view thereof;

FIG. 166 is a top plan view thereof;

FIG. 167 is a front elevational view of a forty-seventh embodiment of a combined vehicle ornament and advertising device;

FIG. 168 is a side elevational view thereof, shown with the central panel rotated;

FIG. 169 is a perspective view thereof;

FIG. 170 is a top plan view thereof;

FIG. 171 is a front elevational view of a forty-eighth embodiment of a combined vehicle ornament and advertising device;

FIG. 172 is a side elevational view thereof, shown with the central panel rotated;

FIG. 173 is a perspective view thereof;

FIG. 174 is a top plan view thereof;

FIG. 175 is a front elevational view of a forty-ninth embodiment of a combined vehicle ornament and advertising device;

FIG. 176 is a side elevational view thereof, shown with the central panel rotated;

FIG. 177 is a perspective view thereof;

FIG. 178 is a top plan view thereof;

FIG. 179 is a front elevational view of a五十th embodiment of a combined vehicle ornament and advertising device;

FIG. 180 is a side elevational view thereof, shown with the central panel rotated;

FIG. 181 is a perspective view thereof;

FIG. 182 is a top plan view thereof;

FIG. 183 is a front elevational view of a fifty-first embodiment of a combined vehicle ornament and advertising device;

FIG. 184 is a side elevational view thereof, shown with the central panel rotated;

FIG. 185 is a perspective view thereof;

FIG. 186 is a top plan view thereof;

FIG. 187 is a front elevational view of a fifty-second embodiment of a combined vehicle ornament and advertising device;

FIG. 188 is a side elevational view thereof, shown with the central panel rotated;

FIG. 189 is a perspective view thereof;

FIG. 190 is a top plan view thereof;

FIG. 191 is a front elevational view of a fifty-third embodiment of a combined vehicle ornament and advertising device;</
